(57) **CLAIM**

The ornamental design for a flexible holder for clips used with a radio controlled vehicle, as shown and described.

DESCRIPTION

FIG. 1 is a top perspective view of a flexible holder for clips used with a radio controlled vehicle showing my new design with a generic vehicle shown in phantom;

FIG. 2 is a top plan view thereof;

FIG. 3 is a bottom plan view thereof and a reverse view of FIG. 2;

FIG. 4 is an end plan view thereof with the reverse view of FIG. 4 having a same appearance; and,

FIG. 5 is a side view thereof the reverse view of FIG. 5 having a same appearance.

The broken lines shown in FIG. 1 are for illustrative purposes only and form no part of the claimed design.
